UNITED STATES PATENT OFFICE.

WILBUR L. COLLINS, OF BALDWINSVILLE, NEW YORK, ASSIGNOR TO EDWARD L. MONTAGUE, JOHN W. MONTAGUE, AND J. KENT WRIGHT, ALL OF BALDWINSVILLE, NEW YORK, AND LEWIS N. OSTRANDER AND ADDISON D. MERRY, BOTH OF PHOENIX, NEW YORK.

DUMPING-WAGON.

968,511.

Specification of Letters Patent. Patented Aug. 23, 1910.

Application filed January 27, 1908, Serial No. 412,895. Renewed May 28, 1910. Serial No. 563,975.

To all whom it may concern:

Be it known that I, WILBUR L. COLLINS, of Baldwinsville, in the county of Onondaga and State of New York, have invented a 5 certain new and useful Dump-Wagon, of which the following is a specification.

My invention relates to dump wagons and has for its object the production of a particularly simple and efficient means for re- 10 turning the dumping doors to their closed position and for holding the same in such position; and to this end it consists in the combinations and constructions hereinafter set forth and claimed.

15 In describing this invention, reference is had to the accompanying drawing in which like characters designate corresponding parts in all the views.

Figures 1 and 2 are respectively front 20 and rear elevations of the box of my dump wagon, the dumping doors being shown as closed in Fig. 1, and open in Fig. 2. Fig. 3 is an inverted plan partly broken away of the bottom of the box. Fig. 4 is a plan 25 of the operating mechanism and adjacent parts of the body of the wagon. Fig. 5 is an elevation looking to the right of the parts seen in Fig. 4.

1 is the box of my dump wagon having 30 dumping doors 2, which meet at substantially the longitudinal center of the box, the doors inclining upwardly and outwardly from their meeting edges. Said doors are provided with upwardly extending supporting members 3 and 4 at their front and rear ends, which are pivoted at 5 and 6, respectively, to the front and rear end boards of the box, the pivots 5 and 6 being located nearer the outer edges of the doors than the inner 35 edges so that the doors will swing outwardly when released, under the weight of the load. One of the front members 3 is provided with an upwardly extending arm 7, and one of the rear members 4 is also provided 40 with a similar arm 8, and links 9 and 10 connect, respectively, the arm 7 and the other front member 3, and the arm 8 and the other rear member, said links 9 and 10 serving to transmit the motion of one door to the 45 other and to equalize the movement of the doors.

The doors are normally held in their closed positions by locking means carried by and swinging with one of the doors 2,

said locking means comprising a rock-shaft 55 11 extending lengthwise of one of the doors 2 near the meeting edges of the doors and latches 12 mounted on the rock-shaft and extending beyond the meeting edges of the doors, each latch being provided with a 60 shoulder 14, which interlocks with a depending lip 15 extending along the inner edge of the opposite door 2, and with a cam-face 16 in advance of the shoulder 14. The rock-shaft is turned in one direction to move the 65 latch into operative position by a spring 17 which is connected at one end to an arm 18 mounted on the rear end of the rock-shaft 11 and at its other end to the corresponding member 4. Such rock-shaft is operated to 70 move the catch 12 out of operative position against the action of the spring 17 by a lever 19 mounted on the front end of a forwardly extending rock-shaft 20 located in front of the box and journaled in bearings formed in blocks or brackets 21 secured to the inner face of the neck 22 of the body of the wagon, the rock-shaft 20 being provided at its rear end with a rock-arm 23 which is connected to the rock-arm 24 carried on the front end of the shaft 11 by a link 25. Obviously, when the lever 19 is depressed, motion will be transmitted to the rock-shaft 11 through the rock-shaft 20, arm 23, link 25, and arm 24, and the latches 85 12 will be moved outwardly disengaging their shoulders 14 momentarily from the lip 15 so that the doors will be opened by the weight of the load in the box. As the doors are approaching their closed positions, the 90 cam faces 16 of the latches 12 engage the lip 15 so that the latches are depressed and the rock-shaft 11 rocked against the action of the spring 17 until the doors have reached their closed position when the shoulders 14 95 again interlock with the lip 15.

This dump wagon is provided with means independent of the locking means for returning the doors to their closed position, this means consisting of a foot lever 26 100 and connections between said lever and one of the front supporting members 3 of the dumping doors. Said connections comprise a rock-shaft 27, extending parallel to the rock-shaft 20 and journaled in bearings formed in the blocks or brackets 21 and carrying rock-arms 28 and 29 at its front and rear ends respectively, and links 105

30 and 31 connecting, respectively, the front arm 28 and the foot lever 26, and the rear arm 29 and the arm 7 of one of the door-supporting members 3. My dump wagon is therefore provided with two forwardly extending rock-shafts arranged side by side and journaled in the same bearing-block, these shafts being operable independently of each other and connected respectively to the locking mechanism and to the doors.

What I claim is:—

1. In a dump wagon, a box having dumping doors movable outwardly in opposite directions, locking means for holding the doors in their closed position, two forwardly-extending rock-shafts arranged in front of the box, one being connected at its rear end to both of the doors for moving the same and the other being connected at its rear end to the locking means, and operating levers connected, respectively, to the front ends of said shafts, substantially as and for the purpose described.

2. In a dump wagon, a box having dumping doors movable outwardly in opposite directions, means for locking the doors in their closed position, two forwardly-extending rock-shafts supported by the neck of the wagon, one being connected at its rear end to both of the doors for moving the same and the other being connected at its rear end to the locking means, and operating levers connected to the front ends of said shafts, substantially as and for the purpose set forth.

3. In a dump wagon, a box having dumping doors movable outwardly in opposite directions, means for locking the doors in their closed position, two forwardly-extending rock-shafts supported by the neck of the wagon and arranged side by side, one being connected at its rear end to both of the doors for moving the same and the other being connected at its rear end to the locking means, and operating levers connected to the front ends of said shafts, substantially as and for the purpose specified.

4. In a dump wagon, a box having dumping doors swinging outwardly in opposite directions, the inner edges of the doors meeting when the doors are closed, locking means for normally holding the doors from opening, said means comprising a rock-shaft arranged on the lower face of one door near the meeting edges of the doors, and a latch mounted on the rock-shaft and extending beyond the meeting edges of the doors and engaging the other door, two forwardly-extending rock-shafts located in front of the box, one being connected at its rear end to both of the doors for moving the same and the other being connected at its rear end to the first-mentioned rock-shaft, and oper-

ating levers mounted, respectively, on the front ends of the forwardly-extending rock-shafts, substantially as and for the purpose described.

5. In a dump-wagon, a box having laterally swinging doors, the inner edges of the doors meeting when the doors are closed, and said doors being provided with upwardly extending supporting members at their ends, said members being pivoted to the ends of the box, locking means for normally holding the doors in their closed position, a rock-shaft arranged in front of and extending forwardly from the box and connected to the locking means, an operating lever connected to the forward end of the said rock-shaft, means for closing the doors comprising a rock-shaft extending along the first-mentioned rock-shaft the rear end of the second-mentioned shaft being connected to the supporting member at one end of one of the doors eccentric to the pivot of said member, and an operating lever connected to the front end of the second-mentioned rock-shaft, and means for transmitting the motion of one door to the other, substantially as and for the purpose specified.

6. In a dump-wagon, a box having laterally swinging doors, the inner edges of the doors meeting when the doors are closed, and said doors being provided with upwardly extending supporting members at their ends, said members being pivoted to the ends of the box, a block formed with two bearings fixed to the inner face of the neck of the wagon, locking means for holding the doors in their closed position, the locking means comprising a rock-shaft arranged on the lower face of one of the doors near the meeting edges of the doors and a latch mounted on the rock-shaft and extending beyond the meeting edges of the doors and engaging the other door, two forwardly extending shafts journaled, respectively, in the bearings of said block and connected at their rear ends, respectively, to the supporting member at one end of one of the doors eccentric to the pivot of said member and to the rock-shaft of the locking means, operating levers connected to the front ends of the rock-shafts, and means for transmitting motion from one door to the other, substantially as and for the purpose described.

In testimony whereof, I have hereunto signed my name in the presence of two attesting witnesses, at Syracuse, in the county of Onondaga, in the State of New York, this 17th day of January, 1908.
